UNITED STATES PATENT OFFICE

ALFRED LANSER, OF CORSEAUX-VEVEY, SWITZERLAND

AUTOMATIC ELECTRIC CIRCUIT BREAKER

Application filed October 11, 1929, Serial No. 398,886, and in Luxemburg September 24, 1929.

This invention relates to electric circuit breakers or timing switches and more particularly and directly to an improved apparatus of the mercury type. Among the objects of the invention is to provide an improved apparatus of the character described comprising few and simple parts which shall be easily assembled, which shall be cheap to manufacture, which shall be positive, sensitive and quick in action, and efficient and practical to a high degree in use. An installation of an apparatus embodying this invention in a liquid fuel burning system is shown and described in my copending application, Serial No. 398,130, filed Sept. 30, 1929.

Further objects of the invention will appear in the annexed specification and drawing which latter represents one practical embodiment of same, and in which—

20 Figure 1 is a sectional view of a mercury circuit breaker constructed to embody the invention; and

Figure 2 is a top plan view of the improved apparatus.

25 To provide an automatic, sensitive, differentially and constantly balanced, rapid operating circuit breaker, such for example, as used as a safety device in an oil burning heating installation, as is fully described and shown in my aforesaid copending application, the circuit breaker is positioned adjacent the burner so that it may be subjected directly to the radiating heat emitted by the burner. The circuit breaker functions to connect the 30 motor actuating machinery in connection with the burner so as to close and maintain the power circuit to the motor closed when the burner operates and during the entire period of operation and to open such circuit when the burner goes out or does not light.

Referring now more to the drawing, the circuit breaker constructed to embody the invention is seen to be comprised of two bulbs *a* and *b* made of any suitable material, such as 35 silico-boron glass, each of said bulbs *a* and *b* being formed with a receptacle *a*¹ and *b*¹, respectively, containing a small amount of mercury.

40 Instead of connecting these bulbs in the conventional manner at their lower parts

they are instead provided with an inverted U-shaped tube *c*. The tube *c* extends from the upper part of the bulb *b* into the bulb *a* and is immersed in the mercury contained in the receptacle *a*¹. An electrode *e* is provided 55 which extends through the tube *c* and terminates a distance *d* above the level of the mercury in the receptacle *a*¹. Another electrode *f* extends into the mercury in said receptacle *a*¹.

60 The bulb *a* above the mercury is filled with a suitable gas, such as will not be effected by arcing on making and breaking the circuit.

65 The circuit breaker described above operates quicker in opening and closing the circuit than those of the conventional type used heretofore, because the relative change of level of the mercury required for operating the circuit breaker is less and the transference of gas from the bulb *a* to the bulb *b* and vice versa, takes place more easily and rapidly. For the above reasons the improved circuit breakers will also retain its operating set adjustment and sensitiveness.

70 To further increase the accuracy of the device, the bulbs *a* and *b* may be counter-balanced by providing a second tube *c*¹ which is similar to the tube *c*. The latter extends from the upper part of the bulb *a* into the bulb *b* and is immersed in the mercury contained in the receptacle *b*¹.

75 In order to reduce the height of the column of mercury to be overcome by the gas pressure and to facilitate and accelerate the transference of the gas from one bulb to the other, the ends of the tubes *c* and *c*¹ which are immersed in the mercury, contained in the receptacles *a*¹ and *b*¹, respectively, are cut on the bias.

80 As shown in Figure 1 the ends of the tubes *c* and *c*¹ opposite those immersed in the mercury extend to approximately the middle of the bulb so that the mercury may be transferred from one bulb to the other when found necessary. The bulbs *a* and *b* are suitably shaped as for example being helmet-like to provide for a reserve supply of mercury for allowing adjustment of the circuit breaker as shown in Figure 1 in the bulb *b*.

85 For rigidly interconnecting the bulbs *a* and *b* 100

b, there is provided one or more braces of glass.

To increase the rapidity of actuation of the circuit breaker one of the bulbs as for example *a* is provided with a material for absorbing the radiating heat emitted by a burner in action. This material preferably is applied as a coating over the bulb, as shown in Figure 2. The circuit breaker when installed 10 in the burner system is then positioned so that the bulb *a* forms a screen for the bulb *b*. The operation of the circuit breaker from the above description is apparent.

In the above description the preferred construction of my apparatus has been described. 15 Obviously numerous other modifications of the apparatus may be made without departing from the spirit of the invention.

Having described my invention what I 20 claim as new and desire to secure by Letters Patent is:

1. An automatic rapid electric circuit breaker of the type described comprising a pair of helmet-like bulbs, a cylindrical receptacle depending from each of said bulbs, mercury in said receptacles, a tube interconnecting the upper part of said bulbs, an extension at one end of said tube depending into one of said receptacles, an electrode on said last mentioned receptacle extending into the mercury therein, a second electrode disposed within the said extension at a predetermined distance from said last mentioned mercury, and an inert gas in said bulbs.

2. An automatic rapid electric circuit breaker of the type described comprising a pair of helmet-like bulbs, a cylindrical receptacle depending from each of said bulbs, mercury in said receptacles, a tube interconnecting the upper part of said bulbs, an extension at one end of said tube depending into one of said receptacles, an extension near the other end of said tube extending into said other receptacle, an electrode in one of said receptacles extending into the mercury therein, a second electrode disposed in the extension corresponding to said last mentioned receptacle at a predetermined distance from the mercury therein, and an inert gas in said bulbs.

3. An automatic rapid electric circuit breaker of the type described comprising a pair of helmet-like bulbs, a cylindrical receptacle depending from each of said bulbs, mercury in said receptacles, a tube interconnecting the upper part of said bulbs, an extension at one end of said tube depending into one of said receptacles, said extension having its free extremity cut on the bias, an extension 60 near the other end of said tube extending into said other receptacle, said second extension having its free extremity cut on the bias, an electrode in one of said receptacles extending into the mercury therein, a second electrode 65 disposed in the extension corresponding to

said last mentioned receptacle at a predetermined distance from the mercury therein, and an inert gas in said bulbs.

4. An automatic rapid electric circuit breaker of the type described comprising a pair of helmet-like bulbs, a cylindrical receptacle depending from each of said bulbs, mercury in said receptacles, a tube interconnecting the upper part of said bulbs, an extension at one end of said tube depending 70 into one of said receptacles, said extension having its free extremity cut on the bias, an electrode on said last mentioned receptacle extending into the mercury therein, a second electrode disposed within the said extension at a predetermined distance from said last mentioned mercury, and an inert gas in said bulbs.

5. An automatic rapid electric circuit breaker of the type described comprising a pair of helmet-like bulbs, a cylindrical receptacle depending from each of said bulbs, mercury in said receptacles, a tube interconnecting the upper part of said bulbs, an extension at one end of said tube depending 80 into one of said receptacles, an electrode on said last mentioned receptacle extending into the mercury therein, a second electrode disposed within the said extension at a predetermined distance from said last mentioned 85 mercury, an inert gas in said bulbs, and a heat-absorbing material covering the bulb of said last mentioned receptacle.

6. An automatic rapid electric circuit breaker of the type described comprising a pair of helmet-like bulbs, a cylindrical receptacle depending from each of said bulbs, mercury in said receptacles, a tube interconnecting the upper part of said bulbs, an extension at one end of said tube depending 100 into one of said receptacles, an electrode on said last mentioned receptacle extending into the mercury therein, a second electrode disposed within the said extension at a predetermined distance from said last mentioned 105 mercury, an inert gas in said bulbs, and a plurality of bracing cross-pieces interconnecting said tubes.

7. An electric circuit breaker of the character described comprising a pair of horizontally spaced bulbs, an inert gas in said bulbs, an inverted U-shaped tube interconnecting said bulbs, an electrode extending through said tube, and mercury in one of said bulbs for contacting with said electrode.

8. An electric circuit breaker of the character described comprising a pair of bulbs, an inert gas and mercury in said bulbs, a pair of inverted U-shaped tubes interconnecting said bulbs, having an end of each immersed in said mercury, an electrode extending through one of said tubes for contacting with the mercury in one of said bulbs.

9. An electric circuit breaker of the character described comprising a pair of bulbs,

an inert gas and mercury in each bulb, a first inverted U-shaped tube interconnecting said bulbs, one end of the first tube extending into one of the bulbs and the other end thereof immersed in the mercury contained in the other bulb, a second inverted U-shaped tube interconnecting said bulbs, one end of the said second tube extending into the last mentioned bulb, the other end of said second tube immersed in the mercury contained in the first mentioned bulb, and an electrode extending through one of said tubes for contacting with the mercury.

10. A device as defined in claim 7 in which one of said bulbs includes a heat absorbing material.

15. In testimony whereof I have affixed my signature.

ALFRED LANSER.
